UNITED STATES PATENT OFFICE.

LEONARD ATWOOD, OF BOSTON, MASSACHUSETTS.

CARBURETER.

1,073,727.

Specification of Letters Patent. Patented Sept. 23, 1913.

Application filed April 14, 1909. Serial No. 489,757.

To all whom it may concern:

Be it known that I, LEONARD ATWOOD, a citizen of the United States, residing in Boston, Massachusetts, have invented certain 5 Improvements in Carbureters, of which the following is a specification.

One object of my invention is to provide an improved device for mixing air with gasoline, or other liquid fuel, in predetermined 10 and constant proportions, which shall be relatively simple in construction, easily operated by inexperienced persons, and not liable to get out of order.

I further desire to provide a carbureter 15 which in addition to being compact in form and occupying but little space, shall be capable of separating the liquid fuel from any water which may be mixed with it, as well as preventing the delivery of fuel to the engine in liquid form.

Another object of the invention is to provide a carbureter which shall give a uniform feed of fuel under the action of capillary attraction and which shall be capable 25 of preventing any dirt or sediment, etc., passing from the fuel tank to the engine; it being also desired that the carbureter shall have its parts so arranged as to at all times deliver air and gasoline in the same fixed 30 proportions, regardless of whether the actual amount of fuel supplied be large or small.

In addition, I wish to provide a device for vaporizing liquid fuel which shall operate 35 by causing the passage of such fuel through a fabric whereby the vaporization is accomplished without the lowering of its temperature which ordinarily occurs when it is required to pass over cold metal surfaces;— 40 the construction of said device being such that it permits any fuel vaporized in the reservoir to escape to the engine without the possibility of its accumulating in said reservoir.

45 These objects and other advantageous ends I secure as hereinafter set forth, reference being had to the accompanying drawings, in which:—

Figure 1, is a side elevation, partly in section, illustrating the detail construction of 50 my device;—Fig. 2, is an enlarged vertical section illustrating the carbureter proper and showing it as slightly modified so as to be supplied with gasoline from a fuel tank connected to a fuel reservoir; Fig. 3, is a 55 vertical section of a slightly modified form

of carbureter; and Fig. 4, is a side elevation of the carbureter shown in Fig. 3.

In Fig. 1 of the above drawings, A represents a reservoir for liquid fuel; B is the carbureter and C is the conduit connecting such carbureter with the valve chest or cylinder of an internal combustion engine of any desired type; there being also a pipe a connecting the carbureter B with the fuel tank A, into which it extends to a point near the bottom thereof. The portion of said pipe within the reservoir A is perforated and a suitable wick of asbestos, cloth or other suitable material extends throughout 70 said tube or pipe to and into the carbureter B. This latter consists of a substantially cylindrical casing b having a projection b' at one side in which is mounted an inwardly opening check valve b''. Extending vertically within the carbureter is a metallic cylinder D, the casing b having an opening at its top and concentric with said cylinder but closed by a valve d mounted therein.

It will be noted that the pipe for delivering fuel from the carbureter to the engine is connected to the top part of said carbureter, and the cylinder D opposite the opening to said pipe is provided with perforations d' to permit of the passage of air or vapor 85 from the interior of said cylinder to said pipe.

In Fig. 2 the valve d is loosely mounted upon a rod or stem d² having a nut d³ serving as an upper abutment for said valve and provided with a spring d⁴ confined on the stem between the valve d and a second valve d⁵. This second valve is in the form of an elongated sleeve slidably, like the valve d, within the cylinder D though it does not move independently of the stem d² and when in its closed position covering a second series of openings d⁶ in the sides of said cylinder opposite the projection b', in which is mounted a check valve b''.

The valve d⁵ is held to the rod d² by means of a nut d⁷ on the lower end thereof and for the purpose of moving said rod and with it the valves, I connect to the upper end of the rod any desired form of manual operating mechanism, such for example as the lever E whereby it may be raised and lowered at will, to uncover more or fewer of the openings in the cylinder D.

The check valve b'' is provided with an 110 adjustable stop b⁸ which fits into a recess in its upwardly extending top portion and may

be raised or lowered as desired, so that the amount of valve opening may be regulated and it is normally held to its seat by a spring b^4 which, however, may be compressed to permit opening of the valve when this latter is drawn upwardly by the suction of the engine piston.

Surrounding the metallic cylinder D is a tubular wick F, Figs. 2 and 3 which extends from an annular partition b^5 separating the upper part or mixing chamber of the carbureter casing adjacent to the outlet pipe C, to the bottom of said cylinder. In the form of my invention shown in Fig. 1 this wick F is engaged by one end of the wick a^2 which leads through the pipe a of the fuel reservoir A, though in the slightly modified form of my invention shown in Fig. 2, it with the lower end of the cylinder D, extends into a small tank G wherein a constant level of gasoline or other fluid fuel is maintained by means of a float g and a valve g' connected thereto. This valve is seated in a conduit g^2 leading from the fuel reservoir and is designed to be actuated by the float to cut off further entrance of liquid to the tank G when such liquid has attained a predetermined depth therein; it being understood that in this case said fuel reservoir is placed at such a level as to properly supply the fuel. In this case an abutment g^5 is fixed to the bottom of the tank G and projects upwardly within the lower part of the cylinder D so as to be engaged by the lower end of the rod d^2 to limit the possible downward movement of said rod with its valves d and d^5 . As shown, there is also a series of perforations or holes g^8 in the lower portion of the cylinder D where this extends within the tank G; through which fuel vapor may be drawn into the interior of the cylinder D, though these holes may be omitted without departing from my invention.

With the above described arrangement of parts in the positions shown, the passage of combustible vapor except on the suction stroke to the pipe C and thence to the engine is prevented, since the sleeve valve d^5 effectually prevents the passage of fuel to the upper portion of the carbureter. It is possible, however, to turn the engine over by hand, for under the action of the suction so produced in the pipe C and in the mixing chamber of the carbureter, the valve d is drawn downward against the action of the spring d^4 and uncovers certain of the upper openings d' of said cylinder, so that air is free to pass into the carbureter through the top opening thereof and thence to the pipe C. After the suction stroke the valve d is again free to be returned to its upper or closed position under the action of the spring d^4 .

If it be desired to admit fuel to the engine, the rod d^2 is moved downwardly by

means of any operating device attached to the lever E so that the valve d uncovers certain of the holes d' above it at or about the same time the valve d^5 likewise uncovers certain of the holes d^6 above itself so that air may be drawn through the wick F and those of said holes above the valve d^5 into the cylinder D, at the same time that a further body of air is drawn into the upper end of said cylinder D through those of the holes d' above the valve d , into the pipe C.

Since liquid fuel is supplied to the lower end of the wick F either from the tank G or from the wick a^2 , this latter is kept in a saturated condition. Moreover upon each suction stroke of the engine air is drawn into the carbureter not only through the uncovered holes d' but also through the wick F and through the holes d^6 in the cylinder D, the valve b^2 being automatically lifted for this purpose. It is therefore obvious that in passing through the saturated wick, the air from the valve b^2 is caused to vaporize and carry with it a definite amount of fuel which is further mixed with the air passing the valve d .

It will be noted that the proportions of fuel and air admitted to the carbureter to form the mixture are normally constant, irrespective of the quantities of said mixture used, since the two valves d and d^5 ordinarily open at approximately the same time to a fixed amount. Under certain abnormal conditions however, the valve d may move independently of the valve d^5 by compressing the spring d^4 , as for example, when the engine is turned over by some external force. It may be noted that this resilient connection between the valves d and d^5 provided by the spring d^4 is particularly advantageous in case the engine was cranked by electric or other power while said valve d^5 is in its closed position, for under this condition, the valve d could open independently to admit air. The arrangement would also be of value in case the vehicle upon which is mounted the engine employing the above described carbureter was moving down grade with the fuel supply valve closed, since free air would be taken in by reason of the opening of the valve d , thus cooling the engine cylinders.

When the auxiliary tank G is used, the float g and valve g' maintain the fuel therein at a constant level, while in the slightly different form of the invention shown in Fig. 1, the wick a^2 accomplishes the same purpose.

In order that there may be no possibility of fuel in a liquid form passing from the carbureter to the engine, I mount in the tube C a tubular or other wick c so that this can absorb and hold any temporary surplus or liquid particles which might, under some

conceivable conditions, be delivered from the carbureter. It is obvious that such surplus would from time to time be taken up by the mixture passing normally from the carbureter so that it serves as a regulating device 5 to prevent improper amounts of fuel being delivered to the engine.

If found advisable, I may, as shown in Fig. 3, provide a third valve d^8 , mounting this upon an extension d^9 of the rod d^2 and extending the perforated cylinder below the tank G as indicated at D'. This extension has a series of perforations d^{10} below which the valve d^8 may be moved so as to admit 10 more or less air into the lower part of the cylinder D, depending upon the number of said perforations uncovered above said valve. As before, however, the relative amounts of air and fuel mixed and delivered 15 to the engine through the pipe C are constant; being customarily in the proportions of nine parts of air to one part of gasoline.

As shown in Fig. 3, I may, when it is desired to secure greater uniformity of feed, as well as an increased supply of fuel provide the main wick F with a reinforcing wick F', surrounding that part thereof to which fuel is supplied so as to insure a fuller 20 and more uniform supply of such fuel than would be ordinarily obtained. If desired, I may deliver liquid fuel to this auxiliary wick through the wick a^3 connected with the fuel reservoir and wound around said auxiliary wick within the carbureter. It is of course obvious that with the construction shown in Fig. 3, there would be provided 25 passages d^{11} through the valve d^5 to permit of the passage of the air entering the cylinder D' through the holes d^{10} .

If desired, the relative positions of the valves d and d^5 may be varied to regulate the relative amounts of air and fuel drawn to the engine, this being accomplished in the 30 form of the invention shown in Figs. 1 and 2, by means of a nut d^3 whereby the position on said valve d upon the rod d^2 may be adjusted. By this change of position of said valve it may be open simultaneously with the 35 valve d^5 or before or after the same, as may be found advisable. Similarly the amount of air admitted through the valve b^2 may be regulated by adjusting the possible lift of the valve by the stop b^3 .

In order to guard against the blowing outwardly of the wick or setting fire to the liquid or vapor in the carbureter, I provide a metallic gauze casing F² Figs. 1 and 3 surrounding the wick F so that this is effectually held in place for the purpose noted. In some cases I may also provide a relief valve b^6 as in Fig. 3 which is preferably mounted in the wall of the casing B in line with the conduit C, and the valve proper b^7 40 is normally held seated by a light spring b^8 ,

although the suction from the engine is ordinarily sufficient to hold it in place. In the event of back firing this valve automatically opens and relieves any excessive pressure within the casing.

It is to be noted that one of the advantages of providing a tubular wick within the conduit leading from the reservoir A to the casing B is due to the fact that any vaporized fuel or gas which may collect in the upper portion of the reservoir is permitted to escape therefrom under conditions of operation and so to the engine through the interior of the wick, thereby obviating any abnormal pressure which might otherwise occur within the reservoir due to its becoming heated.

I claim:—

1. The combination of a casing having two air inlets, and an outlet connected to an engine; a tubular wick in the casing between one of the air inlets and the outlet; means for delivering liquid fuel to the wick; with valves having means for simultaneously actuating them; said valves respectively controlling the flow of air into the casing through the second air inlet and the flow of vaporized fuel from the wick.

2. The combination in a carbureter of a casing having a carbureting chamber connected to an engine and provided with an air inlet to said chamber, a valve for said inlet, a source of supply of liquid fuel connected to another portion of the casing, a wick in the casing placed to receive said fuel from said source, means for delivering air to the wick, and means for controlling the flow of air through the wick to the carbureting chamber, said controlling means being operatively connected to the air inlet valve.

3. The combination in a carbureter of a casing, a wick mounted therein and connected to a source of supply of liquid fuel, means for connecting the casing with the engine, valves placed to respectively govern the flow of air through the wick and the entrance of air into the casing, said valves being mechanically connected and formed to maintain substantially constant the relative proportions of air and vaporized fuel irrespective of the quantities of said ingredients.

4. The combination in a carbureter of a casing, having an outlet, a cylinder, a wick adjacent to the cylinder and connected to a source of liquid fuel, there being air inlets for the casing of which one is placed to deliver air directly to the outlet and another is placed to deliver air to said outlet through the cylinder and the wick, with mechanically connected valves for the cylinder for regulating the flow of air into the casing and also the flow of vaporized fuel from the wick.

5. The combination in a carbureter of a

casing, having an outlet, a cylinder, a wick adjacent to the cylinder and connected to a source of liquid fuel, there being air inlets for the casing of which one is placed to deliver air directly to the outlet and the other is placed to deliver air to said outlet through the cylinder and the wick, with valves for the cylinder for regulating the flow of air into the casing and also the flow of vaporized fuel from the wick, and a common operating device for the valves, said valves being constructed to maintain substantially constant the relative proportions of said vaporized fuel and air regardless of the extent of their openings.

6. The combination of a casing, a cylinder therein having two series of perforations, a valve, and operating means therefor for controlling the flow of air through said cylinder and through one set of perforations, a wick mounted on the cylinder adjacent the other set of perforations and connected to a source of liquid fuel supply, a second valve in the cylinder capable of regulating the flow of air through said wick and through the other set of perforations, said second valve being connected to the first valve, means for admitting air into the casing around the wick, and means for operating the valves.

7. The combination in a carbureter of a casing having a fuel inlet and means for volatilizing liquid fuel, a valve for admitting air to the casing, a second valve for governing the flow of volatilized fuel through the casing, and means for yieldingly connecting said valves while permitting their simultaneous adjustment to permit of independent movement of the valves under predetermined conditions.

8. The combination in a carbureter of a casing having two air inlets and an outlet, a check valve for one inlet, a cylinder in the casing communicating with the other inlet, two valves within the cylinder of which one controls the passage of air through the second air inlet, there being perforations in the cylinder controlled by the other valve, a wick surrounding the cylinder over the perforations and adjacent to the first air inlet, said wick being in communication with a source of fuel supply, and means connecting said two valves for simultaneously operating the same.

55 9. The combination in a carbureter of a casing having two air inlets and an outlet, a check valve for one inlet, a cylinder in the casing communicating with the other inlet, two valves within the cylinder of which one controls the passage of air through the second air inlet, there being perforations in

the cylinder controlled by the other of the valves, a wick surrounding the cylinder over the perforations and adjacent to the first air inlet, said wick being in communication with a source of fuel supply, means connecting said two valves for simultaneously operating the same, and a spring interposed between the valves for permitting one of them to operate independently of the other under predetermined conditions.

10. The combination in a carbureter of a casing having two inlets and an outlet; a cylinder within the casing provided with two sets of perforations of which one set is adjacent the outlet and the other set is adjacent one of the inlets; two valves for the cylinder of which one controls the flow of air from one air inlet to the outlet, and the second valve controls the flow of air from the other inlet through one set of perforations into the cylinder; with a wick around a part of the cylinder.

11. The combination of a carbureter, a reservoir, a conduit connecting said carbureter and the reservoir, and a wick extending in the conduit from the reservoir to the carbureter, with means in the carbureter independent of said wick for vaporizing fuel, said wick having a passage for the transmission of vapor from the reservoir to the carbureter.

12. The combination of a carbureter, a fuel reservoir, a conduit extending from the carbureter to the reservoir and downwardly through the latter to a point adjacent to the bottom thereof, there being openings in the wall of the conduit where it passes through the upper portion of the reservoir, and a tubular wick extending in the conduit from the reservoir to the carbureter.

13. The combination in a carbureter of a casing connected to a source of fuel supply and to an engine; a tubular perforated supporting structure within the carbureter and having its interior connected to the fuel pipe leading to the engine; a tubular wick mounted upon the outside of said structure; and a body of perforated material mounted on the outside of the wick so as to confine it to the perforated supporting structure; the space in the casing immediately surrounding said body of perforated material being in connection with the source of fuel supply.

In testimony whereof, I have signed my name to this specification, in the presence of two subscribing witnesses.

LEONARD ATWOOD.
